UNITED STATES PATENT OFFICE.

GEORGE FRANKE, OF BALTIMORE, MARYLAND.

DESIGN FOR A PAPER LANTERN.

SPECIFICATION forming part of Design No. 16,390, dated November 24, 1885.

Application filed May 15, 1885. Serial No. 165,627. Term of patent 3½ years.

To all whom it may concern:

Be it known that I, GEORGE FRANKE, a citizen of the United States, residing at Baltimore, in the State of Maryland, have invented a new and original Design for Paper Lanterns, of which the following is a specification.

My invention relates to a design for a paper lantern.

10 The accompanying drawings illustrate the design.

Figure 1 is a perspective view of the lantern-case. Fig. 2 is a side view. Fig. 3 is a top view.

15 The lantern-case is square at the top *a*, and also square at the bottom *b*. Between the top and bottom are four sides, *c*, and at the middle each side forms an outward-bulging angle, *d*. Thus each side presents two faces--one, 20 *e*, above the angle, and one, *f*, below. Each

face is ornamented by some device, such as a star, a circle, a crescent, or anything else. Between each two sides, *e*, is a disconnection or interruption, *g*.

I claim--

25 The herein-described design for lantern-cases, the same consisting of a square top and bottom, four sides, *c*, between the top and bottom, and at the middle each side forming an outward-bulging angle, *d*, and each side 30 presenting two ornamented faces, *e f*, and a disconnection or interruption, *g*, between each two sides, as described and shown.

In testimony whereof I affix my signature in presence of two witnesses.

GEORGE FRANKE.
